**AMPLIFIER FOR A SPLIT CORE ELECTRICAL
MEASURING INSTRUMENT**

Samuel J. Koch, Great Neck, N. Y.

Application July 24, 1958, Serial No. 51,926

Term of patent 14 years

(Cl. D26—1)

FIG. 3.

FIG. 1.

FIG. 2.

FIG. 4.

Figure 1 is a front view of an amplifier for a split core electrical measuring instrument showing my new design.

Figure 2 is a side view thereof.

Figure 3 is an opposite side view thereof.

Figure 4 is a bottom view thereof.

I claim:

The ornamental design for an amplifier for a split core electrical measuring instrument, substantially as shown.
